UNITED STATES PATENT OFFICE.

JOHN C. BALLEW, OF EVANSVILLE, INDIANA.

MACHINE FOR SETTING SAWS.

SPECIFICATION forming part of Letters Patent No. 374,032, dated November 29, 1887.

Application filed June 10, 1887. Serial No. 240,889. (No model.)

To all whom it may concern:

Be it known that I, JOHN C. BALLEW, a citizen of the United States, and a resident of Evansville, in the county of Vanderburg and State of Indiana, have invented certain new and useful Improvements in Machines for Setting Saws; and I do hereby declare that the following is a full, clear, and exact description of the invention, will enable others skilled in the art to which it appertains to make and use the same, reference being had to the accompanying drawings, which form a part of this specification, and in which—

Figure 1 is a perspective view of my improved machine for setting saws. Fig. 2 is a front view of the same. Fig. 3 is a side view. Fig. 4 is a similar view seen from the other side. Fig. 5 is a vertical sectional view taken through the shafts of the rollers. Fig. 6 is a rear view, and Fig. 7 is a top plan view.

Similar numerals of reference indicate corresponding parts in all the figures.

My invention has relation to machines for setting saws, and more especially for machines for setting band-saws; and it consists in the improved construction and combination of parts of a machine in which the saw is drawn between two rollers provided with beveled cogs at their ends meshing with each other, and projecting with their beveled sides above the cylindrical faces of the rollers, as herein-after more fully described and claimed.

In the accompanying drawings, the numeral 1 indicates the bench or other object to which the frame is secured, and this frame consists of a back plate, 2, secured to the bench by means of bolts 3, or similar means, and a forwardly-bent top piece, 4, and a downwardly-bent front piece, 5.

A shaft, 6, is journaled vertically in the top piece of the frame in a bearing, 8, and the upper end of this shaft has a hand-wheel or fly-wheel, 7, provided with a crank, 9, or similar means for revolving it, and a small cog-wheel, 10, secured upon the shaft between the fly-wheel and the bearing, while the lower end of the shaft below the bearing is provided with a beveled pinion, 11. This pinion meshes with a beveled cog-wheel, 12, journaled upon a shaft, 13, secured with its ends in the front and back pieces, and the forward face of this

beveled cog-wheel has a roller, 14, secured to it, formed at its outer end with a number of beveled cogs, 15, projecting with their beveled faces above the periphery of the roller and having the bevels facing inward.

The lower portion of the face of the back piece is formed with rabbeted vertical ways 16, between which a block, 17, slides, having a shaft, 18, projecting from the upper end parallel to the shaft of the upper roller, and the lower end of the block is provided with an outwardly-projecting lip, 19, in which the upper end of a screw, 20, is journaled, the said screw fitting and turning in a screw-threaded perforation, 21, in a lip, 22, projecting from the back plate at the lower ends of the ways, and having a hand-wheel, 23, for turning it.

A roller, 24, is journaled upon the shaft of the sliding block, and is provided with beveled cogs 25, similar to the beveled cogs upon the upper roller and registering with the spaces between the said cogs, which spaces 26 are correspondingly beveled, and this lower roller is provided at its inner end with a cogged rim, 27, which meshes with a similar cogged rim, 28, upon the inner end of the upper roller.

A stirrup, 29, is hinged with its free ends to the lower end of the front piece of the frame, swinging outward, and a set-screw, 30, is fitted in a screw-threaded perforation, 31, in the lower doubled end of the same, having its upper end fitting into a recess or notch, 32, in the outer end of the lower shaft, the said screw serving to retain the lower roller upon the shaft, a washer, 33, being interposed between the end of the roller and the screw.

Two rods, 34, slide in horizontal bearings 35 in the back piece and have horizontal slots or notches 36 in their ends, open at the ends 37 and registering with the space between the rollers, and the rear ends of these rods are united by a yoke, 37, having a screw-threaded perforation, 38, in its middle, in which perforation a screw, 39, fits and turns, the said screw having a suitable hand-wheel, 40, for turning it at its outer end, and having its inner end journaled in a bearing, 41, upon the rear face of the back plate.

A bracket, 42, is formed with a horizontal slot, 43, in its inner arm, with which it slides adjustably upon screws 44 in the forward face

of the front piece, and the other arm of the bracket, which is bent at a right angle to the inner arm, has a frame, 45, sliding upon it with a horizontal recess or groove, 46, having a horizontal slot, 47, through which a screw, 48, passes into the arm of the bracket. The upper and lower ends of this frame are formed with vertical bearings 49, in which a vertical shaft, 50, is journaled, and the lower end of this shaft is provided with a wheel, 51, having ratchet-teeth corresponding to the shape of the teeth of the saw, while the upper end of the shaft is provided with a cog-wheel, 52, which meshes with the pinion upon the vertical drive-shaft.

When the machine is to be used for setting a saw, the screw in the stirrup is screwed down out of engagement with the notch in the shaft, whereupon the stirrup is tilted up and the sliding block drawn down by the screw, drawing the lower roller down. The saw-blade 53 is thereupon inserted between the two rollers, and the sliding block is raised by the screw until the beveled cogs of the rollers press sufficiently against the teeth of the saw to give them the proper set, whereupon the stirrup is tilted down and the screw turned up until it again engages the notch of the shaft. The horizontal rods are now forced forward by means of the screw in the yoke until the back of the saw bears against the inner ends of the slots, and the frame having the vertical shaft is adjusted upon the arm of the bracket and the bracket upon the front piece until the ratchet-toothed feed-wheel engages the teeth of the saw with its teeth, when by turning the drive-wheel the saw will be fed between the rollers and the beveled teeth or cogs of the rollers will alternately set the teeth of the saw to both sides, setting the teeth evenly and in a comparatively short space of time.

It will be seen that a saw may have its teeth set in this machine by a person without any particular skill in setting saws, as it is only necessary to place the saw in the machine and to adjust the guides and the feed-shaft and wheel, when the turning of the drive-wheel will do all the setting, the proximity of the rollers to each other regulating the set of the teeth.

The horizontal slotted rods are adjustable for the purpose of allowing saw-blades of various widths to be set in the machine, and the feed shaft and wheel must be adjustable, so as to bring the wheel to bear against the teeth of the saw and to bring the teeth of the feed-wheel and the teeth of the saw to register, the wheel being adjusted farther out for saws having long teeth and farther in for saws having short teeth.

It follows that other saws besides band-saws may be set in this machine, although it is principally intended for setting band-saws, as the guide-rods and the rollers, as well as the feed, are all adjustable to different thicknesses and widths of saws, as well as to saws having teeth of different lengths.

Having thus described my invention, I claim and desire to secure by Letters Patent of the United States—

70

1. In a machine for setting the teeth of saws, the combination of a roller having means for revolving it and formed at one end with cogs projecting beyond the surface, and having beveled sides facing inward, a similar roller having its cogs meshing with the other roller, and having means for adjusting it toward and from the other roller, horizontally-adjustable slotted guides for the saw registering with the space between the rollers, and a feed-wheel at one side of the rollers, having ratchet-shaped teeth meshing with the teeth of the saw, as and for the purpose shown and set forth.

75

2. In a machine for setting the teeth of saws, the combination of a roller having means for revolving it and formed at one end with cogs projecting beyond the surface, and having beveled sides facing inward, and provided at the other end with a cogged rim, a block sliding in ways and having means for adjusting it toward or from the roller, and provided with a shaft projecting parallel to the shaft of the roller, a roller similar in shape to the other roller, having its beveled cogs meshing with the beveled cogs of the other roller, and having a cogged rim meshing with the other rim, and horizontal guides registering with the part of the rigid roller nearest to the movable roller, as and for the purpose shown and set forth.

80

3. In a machine for setting the teeth of saws, the combination, with a pair of rollers having beveled cogs at one end meshing with each other, and having the beveled sides facing inward, of rods sliding in horizontal bearings at both sides of the rollers, and having horizontal slots in their ends open at the ends and registering with the space between the rollers, and having their rear ends connected by a yoke, and a screw journaled at one end and having its threaded portion passing through a threaded perforation in the middle of the yoke, as and for the purpose shown and set forth.

85

4. In a machine for setting the teeth of saws, the combination, with a pair of rollers having cogs at one end meshing with each other, and having beveled sides facing inward and projecting beyond the surfaces of the rollers, and provided with means for revolving them, of a feed-wheel at one side of the rollers, having means for revolving it with the rollers, and having ratchet-shaped teeth for engaging the teeth of the saw, as and for the purpose shown and set forth.

90

5. In a machine for setting the teeth of saws, the combination of a frame composed of an upright back piece and a forwardly-bent top piece and a downwardly-bent front piece, a roller journaled upon a shaft secured in the front and back piece, and having a cogged rim at its inner end and means for revolving it, and having cogs at the outer end projecting beyond the surface and having beveled sides

facing inward, a similar roller having its cogged rim and its beveled cogs meshing, and having means for adjusting it toward or from the other roller and journaled upon a shaft 5 having a notch or recess in the under side of its outer end, and a stirrup hinged with its ends to the lower end of the front piece above the lower roller, and having a set-screw in its doubled end bearing with its end in the recess 10 or notch of the adjustable shaft, as and for the purpose shown and set forth.

6. In a machine for setting the teeth of saws, the combination of a frame consisting of an upright back piece and a forwardly-bent top 15 piece and a downwardly-bent front piece, a roller journaled upon a shaft extending through the front and back piece and having means for revolving it, and provided with a cogged rim at its inner end and with cogs at 20 the outer end projecting beyond the surface of the roller and having the inner sides beveled, a block sliding in vertical ways upon the lower portion of the back plate, and having a lip projecting from its lower end and a shaft projecting 25 from the upper end formed with a recess or notch in the under side of the outer end, a screw provided with a hand-wheel at its lower end and turning in a perforated lip upon the back piece, and having its upper end 30 journaled in the lip of the sliding block, a roller similar to the upper roller journaled upon the shaft of the sliding block, and having its cogged rim and beveled cogs meshing, and a stirrup hinged with its ends to the lower end 35 of the front piece and provided with a set-screw having its upper end engaging the recess or notch in the shaft of the sliding block and working in the doubled end of the stirrup, as and for the purpose shown and set 40 forth.

7. In a machine for setting the teeth of saws, the combination of two rollers having cogged rims at the inner ends and cogs at the outer ends projecting beyond the surfaces and having 45 beveled sides facing inward, a vertically-journaled drive-shaft having a pinion engaging a beveled cog-wheel upon the upper roller, and having a small pinion below its fly-wheel, a bracket having a horizontally-slotted arm 50 sliding adjustably upon the front of the frame for the rollers above the upper roller, and having an outwardly-projecting arm, a frame sliding with a horizontally-recessed and slotted central portion upon the outer arm of the 55 bracket, and having vertical bearings at its ends and a shaft in the bearings, provided at the upper end with a cog-wheel meshing with the pinion upon the drive-shaft, and having at its lower end a wheel formed with ratchet-shaped teeth 60 engaging the teeth of the saw,

the said wheel registering with the space between the two rollers, as and for the purpose shown and set forth.

8. In a machine for setting the teeth of saws, the combination of a frame having an upright 65 back piece secured to a bench or other object, and having a forwardly-bent top piece and a downwardly-bent front piece, and provided with vertical ways upon the lower portion of the back piece and with a lip at the lower end 70 of the ways formed with a screw-threaded perforation, a roller having a beveled cog-rim at its inner end, and having a cogged rim next to the beveled rim, and provided with cogs at the outer end, having beveled sides facing 75 inward and projecting beyond the surface of the roller, a vertical shaft journaled in the top piece and having a fly-wheel at the upper end, provided with suitable means for revolving it, and having a pinion under the fly- 80 wheel and a beveled pinion upon the lower end meshing with the beveled rim of the roller, a block sliding in the ways of the back piece and having an outwardly-projecting shaft at the upper end and a lip at the lower end, hav- 85 ing a screw journaled in it turning in the threaded perforation of the lip of the back piece, a roller similar to the upper roller journaled upon the shaft and meshing with the cogged rim and the beveled cogs of the upper 90 roller, a stirrup hinged with its ends to the lower end of the front piece, and having a set-screw in its doubled lower end engaging a notch or recess in the outer end of the shaft of the sliding block, rods having horizontal slots 95 in their forward ends registering with the space between the rollers and sliding in horizontal bearings in the back piece, and pro- 100 vided with a uniting-yoke at the rear ends, a screw journaled with its inner end in the back piece and fitting in a screw-threaded perforation of the yoke, a horizontally-adjustable bracket upon the front piece of the frame, a frame sliding outwardly adjustable upon the bracket, and having vertical bearings in its 105 ends, and a shaft journaled in the bearings, and having a cog-wheel upon the upper end engaging the pinion of the drive-shaft, and a feed-wheel at the lower end registering with the space between the rollers, and provided 110 with ratchet-shaped teeth engaging the teeth of the saw, as and for the purpose shown and set forth.

In testimony that I claim the foregoing as my own I have hereunto affixed my signature 115 in presence of two witnesses.

JOHN C. BALLEW.
